UNITED STATES PATENT OFFICE.

FRANCIS LEVITT IMPEY, OF BIRMINGHAM, ENGLAND, ASSIGNOR TO KALAMAZOO
LOOSE LEAF BINDER COMPANY, OF KALAMAZOO, MICHIGAN.

TEMPORARY BINDER OR LOOSE-SHEET HOLDER.

979,673.

Specification of Letters Patent. Patented Dec. 27, 1910.

Application filed February 23, 1910. Serial No. 545,504.

To all whom it may concern:

Be it known that I, FRANCIS LEVITT IMPEY, a subject of the King of Great Britain, residing at Birmingham, county of Warwick, England, have invented certain new and useful Improvements in Temporary Binders or Loose-Sheet Holders, for which I have obtained British Letters Patent No. 4,660 of 1909, filed February 25, 1909, and 10 of which the following is a specification.

This invention relates to improvements in temporary binders or loose sheet holders.

The main objects of this invention are, First, to provide in a temporary binder or 15 loose sheet holder an improved adjusting mechanism. Second, to provide in a temporary binder or loose sheet holder an improved cover structure. Third, to provide in a temporary binder or loose sheet holder 20 having a back piece, an improved supporting and adjusting means therefor.

Further objects, and objects relating to structural details, will definitely appear from the detailed description to follow.

25 I accomplish the objects of my invention by the devices and means described in the following specification.

The structure described constitutes one effective embodiment of my invention. Other 30 embodiments would be readily devised by those skilled in the art.

The invention is clearly defined and pointed out in the claims.

A structure constituting an effective and 35 preferred embodiment of the features of my invention is clearly illustrated in the accompanying drawing, forming a part of this specification, in which:

Figure 1 is an inside plan view of a structure 40 embodying the features of my invention, the cover being shown open or extended, and portions broken away to better show the structural details. Fig. 2 is a central longitudinal section, parts being shown 45 in dotted lines to better show their arrangement. Fig. 3 is a transverse section taken on a line corresponding to the irregular line 3—3 of Fig. 2. Fig. 4 is an enlarged detail through the adjusting mechanism, taken 50 on a line corresponding to line 4—4 of Fig. 1. Fig. 5 is a detail section taken on a line corresponding to line 5—5 of Fig. 4. Fig. 6 is a detail section taken on a line corresponding to line 6—6 of Fig. 5. Fig. 7 is a detail section taken on a line corresponding to

line 7—7 of Fig. 5. Fig. 8 is an inverted detail plan of the adjusting mechanism. Fig. 9 is a perspective view of the pawl release or trip. Fig. 10 is a view of the pawl release finger piece. Fig. 11 is an enlarged detail section taken on a line corresponding to line 11—11 of Fig. 1. Fig. 12 is a perspective view of one of the pawls 21.

In the drawings, similar reference characters refer to similar parts throughout the several views, and the sectional views are taken looking in the direction of the little arrows at the ends of the section lines.

Referring to the drawings, the covers 1 are preferably formed with chambers therein 70 to receive the adjusting mechanism of the binder. The covers preferably comprise an outer wall 2 and an inner wall 3. At the inner ends of the covers are cover bars 4, which are secured to the inner walls of the 75 covers, as by means of the screws 5. These bars are also preferably provided with arms 6, which extend into the cover chambers, and are secured to the inner walls thereof, as by means of the screws 7.

An outer facing or covering 8 is provided in the structure illustrated. The cover bars 4 are, in the structure illustrated, provided with knuckles 9, which engage the groove-like sockets 10 in the outer faces of the 85 clamping bars 11. These clamping bars are pivotally secured by means of the pintles 12. These pintles are preferably formed of wire bent into the form of links, the wire being arranged through the knuckles and 90 through the holes 13 in the clamping bars and their ends 14 folded down into the grooves 15 provided therefor in the inner faces of the clamping bars. The clamping bars are provided with holes or openings 95 16 for the binding cords 17, (see Fig. 11).

I preferably provide, in this connection, clamping strips 18 through which the binding cords are arranged, the clamping strips being disposed on the inner sides of the 100 clamping bars to prevent the leaves or sheets entering the grooves 15. The binding cords are secured at one end to the cover bar of one cover by means of rivets 45 (see Figs. 1 and 10) and are adjustably connected to 105 the other cover. This adjusting mechanism, in the structure illustrated, comprises a pair of facing ratchet bars 19, which are secured at their inner ends to the cover bar 4. On these ratchet bars is slidably mounted a 110

member 20 to which the binding cords are secured. This member is adjusted on the ratchet bars by means of the pawls 21, which are pivoted at 22 to the head 23 of the adjusting lever 24. The pivots 22 are arranged on opposite sides of the pivot center of the head 23, so that they are alternately actuated as the lever is reciprocated. The lever 24 is mounted on the binding cord member 20.

The pawls 21 are faced oppositely and held yieldingly into engagement with the rack or ratchet bars 19 by means of the spring 25, which is arranged between them. The pawls are preferably provided with lugs 26, with which the ends of the spring are engaged. This spring yieldingly holds the pawls in engagement, as stated, and permits the free movement thereof without danger or liability of being displaced.

The ends of the pawls are preferably turned up to provide stops 27, which engage the shoulder-like stops 28 on the binding cord member 20, thereby limiting the actuating movement of the pawls. To disengage the pawls simultaneously when it is desired to open the mechanism to permit the removal of sheets or leaves, I provide a trip or pawl release 29, which is mounted on the pivot 30 on the binding cord member, the member being provided with upturned flanges 31 to form supports for the pivot. This trip or pawl release is provided with upwardly-projecting wedge-like fingers 32, which simultaneously engage the pawls when the trip is thrown upwardly, withdrawing them from the ratchet bars so that the binding cord member can be shifted freely.

The pawls are preferably provided with longitudinal slots 33, adapted to receive these trip fingers 32. A finger piece 34 is provided for actuating this trip, the finger piece being adapted to be manipulated through the slot 35 in the inner chamber wall. The pivot 30 for the pawl trip or release member 20 is preferably formed integrally with this finger piece 34. (See Fig. 10.)

The trip 29 is provided with a stop or rest 36 for the finger piece 34, so that the finger piece has some movement independently of the trip or release, and may be folded down, as shown in Fig. 1. When the finger piece is in its elevated position, pressure thereon throws the trip or release into engagement with the pawls, and after the pawls are disengaged, the finger piece serves as an opening finger piece. I have also preferably provided a closing finger piece 37, which is mounted on the pivot 38 carried by the flanges 31 on the binding cord member. This finger piece is preferably provided with a spring 39 for normally retaining it in its collapsed position. The spring, in the

structure shown, is in the form of a coiled spring arranged about the pivot 38, one end being connected to the finger piece and the other to the lever. In manipulating the binder, both the finger pieces may be grasped between the thumb and finger and the binding cord moved freely back and forth upon the ratchet bars. In closing the binder, the binding cords are drawn up as tight as convenient by means of the finger pieces and the lever 24 manipulated to actuate the pawls, which will place the binding cords under the desired tension. This provides a mechanism which may be very quickly adjusted to permit the insertion or removal of sheets or leaves. I preferably, in this connection, provide a back strip 40, which is connected at one end to the binding member 20 to telescope into the chamber cover. The other end of the binding strip is adapted to telescope into the other cover, and is yieldingly supported thereon by means of a rod 41 which is carried by the cover member 4, and a member 42 which is slidably mounted on the rod and held yieldingly outward by means of the coiled spring 43 arranged upon the rod. The member 42 is connected to the end of the back strip by means of the straps 44. These straps are preferably formed of sheet metal so that the connection serves as a guide and prevents, to a large extent, lateral motion of the back strip which might result in its getting out of alignment.

I have illustrated and described my improved temporary binder or loose sheet holder in detail in the form in which I have embodied it in practice, and which I find to be a satisfactory embodiment. I am, however, aware that it is capable of considerable variation in structural details without departing from my invention, but as these variations will, no doubt, be obvious to those skilled in the art to which this invention relates, I do not attempt to illustrate or describe the same herein, but I desire to be understood as claiming my invention specifically in the form illustrated, as well as broadly within the scope of the appended claims.

Having thus described my invention, what I claim as new and desire to secure by Letters Patent is:

1. The combination with a cover, of a binding cord; a pair of facing ratchet bars arranged on said cover; a member to which said binding cord is connected, slidably mounted on said ratchet bars; a pair of pawls; a lever on which said pawls are pivoted, pivotally mounted on said binding cord member, said pawls being pivoted to said lever on opposite sides of its pivot center; a coiled spring arranged between said pawls for holding them yieldingly in engagement with said ratchet bars, said pawls

being provided with lugs with which the ends of said spring is engaged; a pawl trip pivotally mounted on said binding cord member and having a pair of wedge-like

5 pawl engaging fingers thereon, said pawls being longitudinally slotted to receive said fingers; an opening finger piece pivotally mounted on said binding cord member to actuate said pawl trip; and a closing finger piece mounted on said binding cord member 10 in an opposed relation to said opening finger piece.

2. The combination with a cover, of a binding cord; a pair of facing ratchet bars arranged on said cover; a member to which said binding cord is connected, slidably mounted on said ratchet bars; a pair of pawls; a lever on which said pawls are pivoted, pivotally mounted on said binding 15 cord member, said pawls being pivoted to said lever on opposite sides of its pivot center; a coiled spring arranged between said pawls for holding them yieldingly in engagement with said ratchet bars, said pawls being provided with lugs with which the ends of said spring is engaged; and a pawl trip mounted on said binding cord member and having a pair of wedge-like pawl engaging fingers thereon, said pawls being longitudinally slotted to receive said fingers. 20

said binding cord is connected, slidably mounted on said ratchet bars; a pair of pawls; a lever on which said pawls are pivoted, pivotally mounted on said binding cord member, said pawls being pivoted to said lever on opposite sides of its pivot center; a coiled spring arranged between said pawls for holding them yieldingly in engagement with said ratchet bars, said pawls being provided with lugs with which the ends of said spring is engaged; and a pawl trip mounted on said binding cord member and having a pair of wedge-like pawl engaging fingers thereon, said pawls being longitudinally slotted to receive said fingers. 135

6. The combination with a cover, of a binding cord; a pair of facing ratchet bars arranged on said cover; a member to which said binding cord is connected, slidably mounted on said ratchet bars; a pair of pawls; a lever on which said pawls are pivoted, pivotally mounted on said binding cord member, said pawls being pivoted to said lever on opposite sides of its pivot center; and a pawl trip mounted on said binding cord member and having a pair of wedge-like pawl engaging fingers thereon, said pawls being longitudinally slotted to receive said fingers. 140

7. The combination with a cover, of a binding cord; a pair of ratchet bars arranged on said cover; a member to which said binding cord is connected; a pair of pawls; an actuating lever for said pawls; a coiled spring arranged between said pawls for holding them yieldingly in engagement with said ratchet bars, said pawls being provided with lugs with which the ends of said spring are engaged; a pawl trip pivotally mounted on said binding cord member, and having a pair of wedge-like pawl engaging fingers thereon; an opening finger piece pivotally mounted on said binding cord member to actuate said pawl trip; and a closing finger piece mounted on said binding cord member in an opposed relation to said opening finger piece. 145

8. The combination with a cover, of a binding cord; a pair of ratchet bars arranged on said cover; a member to which said binding cord is connected; a pair of pawls; an actuating lever for said pawls; a coiled spring arranged between said pawls for holding them yieldingly in engagement with said ratchet bars, said pawls being provided with lugs with which the ends of said spring are engaged; a pawl trip pivotally mounted on said binding cord member, and having a pair of wedge-like pawl engaging fingers thereon; and a finger piece pivotally mounted on said binding cord member to actuate said pawl trip. 150

9. The combination with a cover, of a binding cord; a pair of ratchet bars arranged on said cover; a member to which

said binding cord is connected; a pair of pawls; an actuating lever for said pawls; a pawl trip pivotally mounted on said binding cord member, and having a pair of wedge-like pawl engaging fingers thereon; an opening finger piece pivotally mounted on said binding cord member to actuate said pawl trip; and a closing finger piece mounted on said binding cord member in an opposed relation to said opening finger piece.

10. The combination with a cover, of a binding cord; a pair of ratchet bars arranged on said cover; a member to which said binding cord is connected; a pair of pawls; an actuating lever for said pawls; a pawl trip pivotally mounted on said binding cord member, and having a pair of wedge-like pawl engaging fingers thereon; and a finger piece pivotally mounted on said binding cord member to actuate said pawl trip.

15. The combination with a cover, of a binding cord; a pair of ratchet bars arranged on said cover; a member to which said binding cord is connected, a pair of pawls operatively associated with said member to coact with said ratchet bars; an actuating lever for said pawls; a coiled spring arranged between said pawls for holding them yieldingly in engagement with said ratchet bars, said pawls being provided with lugs with which the ends of said spring are engaged; and a release for said pawls.

20. The combination with a cover, of a binding cord; a pair of ratchet bars arranged on said cover; a member to which said binding cord is connected; a pair of pawls operatively associated with said member to coact with said ratchet bars; an actuating lever for said pawls; and a release for said pawls.

25. The combination with a cover, of a binding cord; a pair of facing ratchet bars arranged on said cover; a member to which said binding cord is connected, slidably mounted on said ratchet bars; a pair of pawls; a lever on which said pawls are pivoted, pivotally mounted on said binding cord member, said pawls being pivoted to said lever on opposite sides of its pivot center; a coiled spring arranged between said pawls for holding them yieldingly in engagement with said ratchet bars, said pawls being provided with lugs with which the ends of said spring are engaged; and means for disengaging said pawls to permit the free adjustment of said binding cord member.

30. The combination with a cover, of a binding cord; a pair of facing ratchet bars arranged on said cover; a member to which said binding cord is connected, slidably mounted on said ratchet bars; a pair of pawls; a lever on which said pawls are pivoted, pivotally mounted on said binding

35. cord member; said pawls being pivoted to said lever on opposite sides of its pivot center; a spring for holding said pawls yieldingly in engagement with said ratchet bars; and means for disengaging said pawls to 70 permit the free adjustment of said binding cord member.

40. 15. The combination with a cover, of a binding cord; a pair of ratchet bars arranged on said cover; a member to which said binding cord is connected; a pair of pawls operatively associated with said member to coact with said ratchet bars; means for actuating said pawls; a coiled spring arranged between said pawls for holding them yieldingly in engagement with said ratchet bars, said pawls being provided with lugs with which the ends of said spring are engaged; and means for disengaging said pawls to 75 permit the free adjustment of said binding 80 cord member.

45. 16. The combination with a cover, of a binding cord; a pair of ratchet bars arranged on said cover; a member to which said binding cord is connected; a pair of pawls operatively associated with said member to coact with said ratchet bars; means for actuating said pawls; a spring for holding said pawls yieldingly in engagement with said ratchet bars; and means for disengaging said pawls to 85 permit the free adjustment of said binding 90 cord member.

50. 17. The combination with a cover, of a binding cord; ratchet bars arranged on said cover; a member to which said binding cord 100 is connected; a pair of pawls operatively associated with said member to coact with said ratchet bars; an actuating lever for said pawls; and a pawl trip pivotally mounted on said binding cord member, and having a pair of wedge-like pawl engaging fingers thereon, said pawls being longitudinally slotted to receive said fingers.

55. 17. The combination with the covers, comprising inner and outer walls forming 105 chambers at the inner ends of the covers; cover bars disposed at the inner ends of the cover and secured to the inner walls thereof; arms on said bars projecting into said cover chambers and secured to the inner cover 110 walls; binding cords connected to one of said cover bars; adjusting means for said binding cords, comprising a member carried by the other cover bar and an adjustable member to which the binding cords are connected, slidably mounted thereon; a back strip adapted to telescope into said chambers, connected at one end to said adjustable member; a rod mounted on the cover bar of the other cover to project into the cover 115 chamber; a member to which the other end of said back strip is connected, slidably mounted on said rod; and a spring arranged on said rod to engage said member, whereby the same is yieldingly supported. 120

19. The combination with the covers, comprising inner and outer walls forming chambers at the inner ends of the covers; cover bars disposed at the inner ends of the covers and secured to the inner walls thereof; arms on said bars projecting into said cover chambers and secured to the inner cover walls; binding cords connected to one of said cover bars; and adjusting means for 5 said binding cords, comprising a member carried by the other cover bar and an adjustable member to which the binding cords are connected, slidably mounted thereon.
20. The combination with the covers, comprising inner and outer walls forming chambers at the inner ends of the covers; cover bars disposed at the inner ends of the cover and secured to the inner walls thereof; binding cords connected to one of said cover 10 bars; adjusting means for said binding cords, comprising a member carried by the other cover bar and an adjustable member to which the binding cords are connected, slidably mounted thereon; a back strip 15 adapted to telescope into said chambers, connected at one end to said adjustable member; a rod mounted on the cover bar of the other cover to project into the cover chamber; a member to which the other end 20 of said back strip is connected, slidably mounted on said rod; and a spring arranged on said rod to engage said member, whereby 25 the same is yieldingly supported.
21. The combination with the covers, comprising inner and outer walls forming cham- 30
- bers at the inner ends of the covers; cover bars disposed at the inner ends of the cover and secured to the inner walls thereof; binding cords connected to one of said cover bars; and adjusting means for said binding 40 cords, comprising a member carried by the other cover bar and an adjustable member to which the binding cords are connected, slidably mounted thereon.
22. The combination with a pair of covers, 45 of clamping bars having hinge-like sockets in their outer faces and longitudinal grooves in their inner faces and holes therethrough opening into said sockets and grooves; hinge members secured to said covers and having 50 knuckles arranged in said sockets; and link-like pintles arranged through said knuckles and said holes in said clamping bars, the inner ends of said links being arranged in 55 said grooves.
23. The combination with a pair of covers, 60 of clamping bars having hinge-like sockets in their outer faces and longitudinal grooves in their inner faces and holes therethrough opening into said sockets and grooves; hinge members secured to said covers and having knuckles arranged in said sockets; and pintles formed of wire arranged through said 65 knuckles and said holes in said clamping bars, the ends of the wires being folded into said grooves.
